DETACHABLE IRONING BOARD CLOTHES SUPPORT RACK

Steve Falcetti, Forest Hill, Queens County, N. Y.
Application March 22, 1956, Serial No. 573,135

4 Claims. (Cl. 38—111)

This invention relates to an ironing board clothes support rack which is adapted to be detachably connected to the sides of the ironing board so as to underlie the tapered end thereof and prevent clothes from touching the floor while being ironed.

It is the principal object of the present invention to provide in a detachable ironing board clothes support rack or extension which can by a simple means and manipulation be easily secured to the opposite sides of the ironing board intermediate its length and wherein there is provided collapsible leg support under the outer end of the rack which is independent of the ironing board and removed therefrom and so as not to interfere with the movement of the clothes being ironed and the passing of the same into the rack.

It is another object of the invention to provide a detachable ironing board clothes support rack which provides for a horizontal support surface lying at the elevation of the top of the ironing board as well as a basket-like portion lying under the tapered end of the board so that the clothes being ironed will be guided over a large area when needed for elongated work pieces and yet permit the use of the basket-like portion free of the horizontal support surface for other work pieces, there being sufficient space allowed between the inner edge of the horizontal support surface and the edge of the ironing board to allow for the passage of the pieces therebetween.

It is another object of the invention to provide an ironing board clothes support rack which has both horizontal and basket portions and wherein the frame piece on the inner edge of the horizontal portion is bendable to conform to the tapered side edge of the ironing board with which the rack is to be used.

It is still another object of the invention to provide in a detachable ironing board clothes support rack having both horizontal and basket portions in which the flexible cloth material forming these portions can be easily slid onto the wire frame work or removed therefrom so that it can be cleaned and made ready again for further use upon the frame work.

It is a further object of the invention to provide an ironing board clothes support rack in which the attaching ends of the wire frame work which are adapted to be attached to either a wood or metal ironing board top merely by the use of different attaching clips that will be fixed to the ironing board sides.

Other objects of the invention are to provide a detachable ironing board clothes support rack which is of simple construction, inexpensive to manufacture, has a minimum number of parts, of pleasing appearance, light in weight, collapsible to consume little space when stored, compact, durable, efficient and effective in use.

For a better understanding of the invention, reference may be had to the following detailed description taken in connection with the accompanying drawing, in which—

Figure 1 is a perspective view of the detachable ironing board clothes support rack with illustration made as to the manner in which it is attached to the ironing board,

2

Fig. 2 is an end elevational view of the ironing board clothes support rack with the supporting leg extended to its down position,

Fig. 3 is an enlarged detail sectional view of the hinged band for the supporting leg as viewed on line 3—3 of Fig. 1,

Fig. 4 is an enlarged detail sectional view taken through the rack frame and the leg when extended and showing the manner in which the leg is secured by the clip in its down or supporting position, the view being taken on line 4—4 of Fig. 2,

Fig. 5 is a vertical sectional view looking upon a clip secured to the side of the metal ironing board and serving as the attaching means for the extensions of the rack frame and illustrating the manner in which the clip is made secure to the metal ironing board, this view being taken on line 5—5 of Fig. 1,

Fig. 6 is a fragmentary longitudinal view looking upon the inner face of the clip attached to the edge of the metal ironing board and as viewed on line 6—6 of Fig. 1,

Fig. 7 is a fragmentary sectional view of an attaching hook such as used when securing the rack to the edge of a wood ironing board top,

Fig. 8 is a fragmentary longitudinal view looking upon the two wire hooks attached to the wood ironing board top and the rack frame extension supported thereon,

Fig. 9 is a top plan view removed from the ironing board and looking upon the wire frame work and the flexible supporting cloth extended thereover, a portion of the cloth being broken away to show the band for retaining the bendable inner frame piece of the horizontal supporting portion, and

Fig. 10 is a sectional view taken on line 10—10 of Fig. 9.

Referring now to the figures, 15 represents generally the detachable ironing board clothes support rack embodying the features of the present invention and adapted for attachment to a collapsible ironing board 16 having either a metal or wood ironing board top 17 with parallel side edges 18 and 19 and a tapered end 17' under which the clothes support rack 15 is adapted to be extended when attached to the sides 18 and 19 of the ironing board top 17 intermediate its length and when its leg 20 is extended to the down position to engage with the floor and in the manner as shown in Figs. 1 and 2.

This support rack 15 has a top frame work 21 formed of a rod of metal which provides two attaching extensions 22 and 23 opposing one another and adapted to lie along the respective opposite sides 18 and 19 of the ironing board. The extension 22 has an inwardly bent end 24 adapted to underlie the edge of the ironing board top and an outwardly extending arm 25 that runs into a side portion 26 that runs along under the tapered end 17' of the ironing board. This side portion rod 26 is depended downwardly by the arm 25 and joins with an outer end 27 lying below the ironing board top and to which there is connected a riser rod portion 28. A horizontal rod portion 29 lies at the elevation of the top of the ironing board. Extending from the outer end of the rod portion 29 is a rod portion 30 that runs parallel to the rod portion 26 and forms the elevated rear edge of the frame work. The inner end of this rod portion 30 has an inwardly extending arm 31 to which the attaching extension 23 is connected. This extension 23 has a bent end 32 adapted to underlie the side 19 of the ironing board 17.

Extending from the extension 23 along the rear side 19 of the ironing board and joined by welding or in any other suitable manner is an intermediate bendable rod or wire 34 having a bend and connected between the extension 23 and the upper end of the riser rod portion 28. This rod 34 divides the frame work and is at the same

elevation as the rear runner rod portion 30. A flexible cover 35 is slidably fitted over the frame work 21. This cover 35 is made of flexible cloth material and has a double sleeve portion 36 adapted to surround the bendable rod 34 and the rear rod 30 so as to provide a horizontal supporting surface at the level of the ironing board top. Depending from the inner edge of this sleeve portion 36 is a basket portion 37 having a hem 38 through which the rod portion 26 extends. This basket portion will underlie the tapered end 17' of the ironing board. The horizontal portion 36 will have its inner edge spaced from the side edge 19 of the ironing board to allow the work pieces to be easily passed from the top of the ironing board into the basket portion 37 lying thereunder.

In order that the intermediate edge of the horizontal portion 36 can be adapted to the edge of differently shaped ironing boards, a band 39 is drawn over the frame work along the rear rod portion 30 and the bendable rod 34 so that the bend of the rod portion 34 can be made at different positions intermediate of the ends thereof and the inner edge of the horizontal surface be made to conform to the edge of the particular ironing board to which the rack is to be connected. Once the band 39 has been made secure upon the rack the adjustment would not thereafter have to be again made for the particular ironing board with which the support rack is being used.

The cover is held in place upon the frame work 21 at the outer end thereof by tabs 40 and 41 on the sleeve portion 26 of the cover that have cooperating snap fastener elements and adapted to be extended over and around the elevated rod portion 29. When it is desired to remove the cover 35 the tabs are detached from one another and the cover is slid outwardly over the frame work extensions 22 and 23.

The leg 20 has a horizontally-bent upper end 42 and a foot 43. The horizontally-bent upper end 42 is hingedly connected to the horizontal portion 29 by hinge bands 44 and 45 so that the leg can be collapsed upon the frame work by simply hinging the same upwardly and under the rack in the manner illustrated in Figure 1. The support rack can be carried upon the ironing board without the leg being extended if the work pieces to be ironed are not too heavy.

When the leg 20 is extended to the down position it 45 will engage as best shown in Fig. 4 a clip 46 fixed to the riser rod portion 28.

In adapting the support rack to a metal ironing board top, clips 47 and 47' as best shown in Figs. 5 and 6 are rested against the side edges and a tab 48 thereof is bent 50 inwardly as illustrated in Fig. 5 to fix the clip to the edge of the ironing board top. The clip has a depending supporting hook portion 49 lying on the outer edge of the ironing board top that receives the extension 22 or 23 while its bent end 24 or 32 extends inwardly under the 55 edge of the ironing board. The frame work is sufficiently flexible to easily position the bent ends 24 and 32 of the extensions under the edges of the ironing board and the extensions rested in the clip depending hook portions 49.

If the ironing board top is made of wood 17a the rack 60 can be secured thereto by means of two wire hooks 51 and 52 threaded into the edge of the wood ironing board, on which the extensions 22 and 23 will be rested while their inwardly bent ends will engage with the undersurface of the ironing board top.

It should now be apparent that there has been provided a detachable ironing board support rack that has

both horizontal and basket supporting portions wherein the horizontal portion lies elevated along one side of the ironing board with its inner edge bendable and adjustable to conform to the edge shape of the ironing board.

It will also be apparent that the support rack is adapted to be supported on either a metal or wood ironing board top simply by use of appropriate clips or hooks that can be readily secured to the side edges of the ironing board top.

10 While various changes may be made in the detail construction it shall be understood that such changes shall be within the spirit and scope of the present invention as defined by the appended claims.

What is claimed is:

1. A detachable ironing board clothes support rack having a frame work with extensions adapted to be secured along the opposite side edges of the ironing board top and to be extended under and along the tapered end of the ironing board, a flexible cover extended over the frame work, said frame work being lowered at the front to provide for a basket portion of the cover and adapted to underlie the end of the ironing board and elevated at the rear thereof to provide a horizontal portion lying at the level of the ironing board so as to be spaced from the rear side edge thereof, an intermediate frame member providing the inner edge of the horizontal supporting portion and bendable to conform to different edges of different ironing boards with which the support rack is used and means for retaining the bent member in its adjusted bent position, said frame work having a riser rod portion and an elevated horizontal rod portion at the front end of the frame work, a foldable supporting leg having a horizontally-bent upper end, means for hingably connecting the upper end to the horizontal portion and means for releasably retaining the leg when extended upon the riser rod portion, said leg being foldable between a vertical position and a horizontal position under the rack.

2. A detachable ironing board clothes support rack as defined in claim 1, and said flexible cover having a large sleeve slidably fitted over the elevated frame work portion whereby to provide a double thickness about the frame horizontal portion.

3. A detachable ironing board clothes support rack as defined in claim 2, and cooperating tabs on the end of the sleeve portion and fastening means for securing the tab portions together to hold the flexible cover against sliding toward the ironing board.

4. A detachable ironing board clothes support rack as defined in claim 1, and attaching clips adapted to be secured to the side edges of the ironing board, said frame attaching extensions having inwardly-bent ends adapted to engage with the under edges of the ironing board while resting in the attaching clips.
